Primary Examiner — Patricia Palasik(74) *Attorney, Agent, or Firm* — Lawrence Letham; Letham Law Firm LLC(57) **CLAIM**

The ornamental design for a robot accessory mount, as shown and described.

DESCRIPTION

FIG. 1 is a perspective view of a robot accessory mount, showing our design, with the top, front, and right side visible; FIG. 2 is a front view of the robot accessory mount of FIG. 1; FIG. 3 is a right side view of the robot accessory mount of FIG. 1; FIG. 4 is a top view of the robot accessory mount of FIG. 1; and, FIG. 5 is a bottom view of the robot accessory mount of FIG. 1.

The front view and the rear view are symmetrically identical. The right side view and the left side view are symmetrically identical.

The broken lines in the drawings depict unclaimed environmental subject matter.

1 Claim, 4 Drawing Sheets(56)
